CLAIM

The ornamental design for a refreshment dispenser, as shown and described.

DESCRIPTION

FIG. 1 is a top, front, and left side perspective view of a refreshment dispenser showing my new design;
FIG. 2 is a front elevational view thereof;
FIG. 3 is a right side elevational view thereof;
FIG. 4 is a rear elevational view thereof;
FIG. 5 is a top plan view thereof; and
FIG. 6 is a bottom plan view thereof.
